GLASS BAKE OVEN WARE LIFTER

Vearl E. Jacobs, Tulsa, Okla.

Application August 16, 1956, Serial No. 604,479

1 Claim. (Cl. 294—31)

The present invention relates generally to kitchen appliances and has for its primary object to provide, in a manner as hereinafter set forth, novel means for safely gripping and lifting hot casseroles and other bake dishes of various sizes and shapes.

Another important object of the invention is to provide a safety lifter of the aforementioned character comprising a handle including removable and replaceable grips having novel securing means.

Other objects of the invention are to provide a safety lifter of the character set forth which will be comparatively simple in construction, strong, durable, highly efficient and reliable in use, compact, of light weight, attractive in appearance and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

Figure 1 is a perspective view of a lifter constructed in accordance with the present invention;

Figure 2 is a view in side elevation, showing the device in use with portions broken away in section;

Figure 3 is a cross-sectional view, taken substantially on the line 3—3 of Figure 2;

Figure 4 is a detail view in side elevation of one of the grips with portions broken away; and

Figures 5 and 6 are detail views taken substantially upon the plane indicated by the section lines 5—5 and 6—6 respectively of Figure 4.

Referring now to the drawing in detail, it will be seen that the embodiment of the invention which has been illustrated comprises a pair of spaced, opposed, substantially semi-circular jaws of suitable wire which are designated generally by reference character 5. The jaws 5 are hingedly or pivotally connected at one end by a sheet metal link or hinge 6.

The jaws 5 are adapted to receive and firmly grip therebetween the top or rim portion 7 of a bake dish 8, for instance. Toward this end, each jaw 5 is formed from a single length of wire bent upon itself at an intermediate point to provide a bight portion 9 which is journaled in the link or hinge 6. Each jaw 5 further includes vertically spaced parallel legs 10 for the reception of the rim and lifting tabs of the bowl 8 therebetween.

The device further includes a handle which is designated generally by reference character 12. The handle 12 includes a pair of complementary grips 13 of suitable material, preferably wood, which are mounted on the free end portions of the jaws 5.

The grips 13 comprise substantially flat, opposed inner faces 14 having elongated recesses 15 extending longitudinally thereinto from the forward ends thereof. The inner or bottom walls of the recesses 15 have formed therein substantially U-shaped grooves or channels 16, see Figures 5 and 6. The grooves 16 are for the reception of the substantially L-shaped free end portions 17 of the legs 10 of the jaws 5. This is shown to advantage in Figure 4 of the drawing. It will be noted that the oppositely angularly bent extremities 18 of the legs 10 are lapped in the bight portions of the substantially U-shaped grooves 16. Thus, the grips 13 are positively

2

anchored against longitudinal movement on the jaws 5. The recesses 15 accommodate metallic plates 19 which retain the elements 17 and 18 in the grooves 16. Suitable screws 20 at spaced points in the grips 13 secure the plates 19 in the recesses 15.

As will be seen best from Figure 1, the ends of each pair of curved legs 10 of a jaw 5 adjacent the hinge 6 have substantially straight, substantially parallel end portions 22 connected by the bight portion 9, the two straight end portions 22 of the jaws projecting laterally and angularly therefrom, thereby offsetting the hinges of the jaws from the curved legs.

It is thought that the use of the lifter will be readily apparent from a consideration of the foregoing. Briefly, 15 the jaws 5 are opened in the manner suggested in Figure 1 of the drawing and positioned astraddle the upper portion of the casserole or bowl to be lifted, as at 8. Through the medium of the grips 13, the jaws 5 are then closed on the bowl for firmly gripping same in an obvious 20 manner. With the substantially flat inner faces 14 of the grips 13 in abutting engagement with each other or substantially so, the device with the bowl clamped therein may be readily lifted with one hand gripping the handle 12. To remove the grips 13 for any reason, it 25 is only necessary to unscrew the bolts 20 thus detaching the plates 19. The jaws 5 may be of various shapes and dimensions to accommodate different bowls, dishes or other containers. Also, the grips 13 may be attractively colored.

30 The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

A glass bake oven ware lifter comprising a centrally 40 located hinge, a pair of substantially semi-circular jaws disposed at opposite ends of said hinge, each of said jaws being in the form of a length of wire bent upon itself at intermediate points to provide spaced parallel legs for receiving therebetween ears and flanges of oven ware, and an intermediate bight portion, said legs of each jaw having substantially straight end portions laterally offset therefrom and connected by said bight portions, said hinge being in the form of a flat, straight strap having end portions in the form of vertically disposed elongated 50 hinge eyes, said bight portions extending through said eyes and being rotatably journaled relative to said hinge, handles on said jaws, said handles having opposed faces, each of said opposed faces having an outer recess terminating in an inner elongated generally U-shaped recess, said legs including end portions having opposed offset ends, said end portions being seated in said inner groove with said opposed offset parts being disposed in overlapping relation, and a retaining plate secured in each of 55 said outer recesses and engageable with said end portion of its respective handle and retaining the respective one of said handles on said leg portions of said jaw.
